CRIMPING APPARATUS

Leo W. Rainard and Ewart H. Shattuck, Wilmington, Del., assignors to Joseph Bancroft & Sons Company, Wilmington, Del., a corporation of Delaware

Application March 18, 1955, Serial No. 495,128

4 Claims. (Cl. 28—1)

This invention relates to apparatus for crimping continuous filament yarn and tow and has for an object to provide an apparatus of the above type having novel and improved characteristics.

Another object is to provide a stuffer crimper having novel and improved means for controlling the length of time the crimped fibers are subjected to setting conditions.

Another object is to provide a stuffer crimper having novel and improved means for introducing a fluid agent into the crimping chamber.

Another object is to provide a stuffer crimper having novel and improved means for varying the size of the crimping chamber.

Other objects and advantages will be apparent as the nature of the invention is more fully disclosed.

The nature of the invention will be better understood by referring to the following description, taken in connection with the accompanying drawing in which a specific embodiment thereof has been set forth for purposes of illustration.

In the drawing:

Fig. 1 is a vertical section through a stuffer crimper embodying the present invention; and

Fig. 2 is a partial horizontal section taken on the line 2—2 of Fig. 1.

Referring to the drawing more in detail a crimping chamber block 10 is shown as attached to a supporting plate 11 by screws 12. The block 10 is formed with a vertical bore in which a sleeve 13 is fixed by a press fit. A tube 14 fits loosely in the sleeve 13 and is adjustably secured by a clamping nut 15 threaded onto the tapered split end 16 of the sleeve 13. The plate 11 carries a bearing in which is journaled a shaft 20 carrying a feed roll 21. A second feed roll 22 is carried on a shaft 23 journaled in a bearing in an arm 24, pivotally attached as by a pin 25 to a bracket 26 which is attached to or carried by the plate 11. The shaft 20 is driven by a source of power such as a motor, not shown. The shaft 23 is driven in unison therewith by meshing gears carried by the respective shafts 20 and 23.

The feed rolls 21 and 22 are held in pressure engagement with the yarn 30 by means of a spring 31 attached to a post 32 on the arm 24 and to a post 33 on the plate 11. Adjustment is provided by threaded pin 33a and nut 34. The yarn 30 is guided to the bite of the feed rolls 21 and 22 by a fixed guide 35 which is attached by a screw 36 to the plate 11.

The lower end of the tube 14 is slotted to form a saddle to receive the rolls 21 and 22 and extends below the bite of the rolls to form therewith a substantially closed crimping chamber 40 into which the yarn 30 is fed for crimping.

The tube 14 is formed with a bore 41 of larger diameter than the crimping chamber 40 and extending from its upper end to a point near the lower end of the block 10 and terminating above the chamber 40 in a tapered shoulder 42. A sleeve 43 is disposed within this bore 41 and is formed at its lower end with a tapered end

2

surface 44 intersecting the inner bore of the sleeve at a knife edge and adapted to rest upon or to be slightly spaced above the tapered shoulder 42 of the tube 14. The sleeve 43 is adjustably held in the tube 14 by a bushing 45 which is clamped against the end of the tube 14 by a cap nut 46. The outer surface of the sleeve 43 is smaller than the bore 41 so as to provide an annular passage 48 extending around the sleeve 43 from the upper portion of the sleeve to the lower end thereof adjacent the shoulder 42. A treating fluid may be introduced into this annular passage by a pipe 49 which is secured to the tube 14 above the block 10 and is controlled by an adjustable valve 50. A suitable setting fluid such as steam or hot water or a chemical setting agent or a dye may be introduced into the crimping chamber through the pipe 49 or the fibers may be oiled by the introduction of controlled quantities of oil through the pipe 49 as desired. In the event that no fluid is to be introduced through the pipe 49 the sleeve 43 is preferably seated against the shoulder 42 of the tube 14 so that a continuous passage is provided for the crimped yarn.

The block 10 may be heated by suitable means as by a Calrod 51 which is inserted in a bore 52 in the block 10 and extends parallel to the tube 14 so as to heat the walls thereof. The Calrod may be controlled so as to raise the fibers in the tube 14 to the temperature necessary for crimping and setting.

In order to introduce oil, a dye, a setting agent, or other material into the sleeve 43 a cup 60 is attached to the sleeve above the block 10. The treating liquid is maintained at a predetermined level in the cup 60 by a tube 61 extending from a reservoir 62 to the predetermined level. The reservoir 62 is attached to the plate 11 above the cup 60. The flow of treating fluid into the sleeve 43 is controlled by a valve stem 63 seating in an opening 64 in the wall of the sleeve 43 and extending through the peripheral wall of the cup 60. The valve stem 63 is provided with a manual adjustment knob 65 and with a suitable bushing 66 to secure the same in adjustable position to the wall of the cup 60.

A plug 67 is inserted in the top of the sleeve 43 to rest upon the crimped yarn 68 within the sleeve. The crimped yarn 68 is withdrawn through the bore 69 of the plug 67 by take-up rolls 70 which may be operated at a constant rate bearing a predetermined relationship to the rate of feed by the feed rolls 21 and 22, which relationship may be adjusted in response to variations in position of the plug 67 so as to maintain the plug at a constant level within the sleeve 43, as shown in Patent No. 2,734,251 issued February 14, 1956.

In operation the feed rolls 21 and 22 feed the yarn 30 into the crimping chamber against the pressure exerted by the mass of crimped yarn in the chamber. The mass of crimped yarn is advanced along the chamber and along the sleeve 43 by the pressure of the incoming yarn and is withdrawn under tension from the top of the chamber by the take-up rolls 70. The yarn in the crimping chamber may be treated by the fluid injected through the pipe 49, which flows downwardly along the sleeve 43 and into the chamber 40 when the sleeve is raised from its seat on shoulder 42. This treatment may be adapted to soften the yarn to facilitate the crimping and setting, or, in the case of yarns which are settable by moisture or other setting agent, such setting agent may be introduced through the pipe 49.

As the crimped yarn is forced upwardly through the chamber and through the sleeve 43 it is maintained under crimping pressure and is heated to a temperature suited to facilitate setting of the crimp by the heated walls of the member 10. At the same time the yarn may be oiled by means of oil supplied from the cup 60.

The length of the sleeve 43 is so selected that the crimp

is completely set in the yarn by the time the yarn reaches the top of the sleeve. The yarn with a permanently set crimp is withdrawn from the top of the sleeve through the plug 67 by the take-up rolls 70.

It is to be understood that if injection of liquid into the sleeve 43 is not required the cup 60 may be omitted. Also that the sleeve 43 may be replaced by a sleeve of a different length or of a different diameter according to the nature of the filaments being crimped and is selected so as to obtain the most efficient crimping condition. Also if it is not desired to introduce a fluid agent into the chamber 40 the pipe 49 may be omitted or the valve 50 closed and the sleeve 43 may be adjusted to bear against the shoulder 42 as above specified. For this purpose the bottom of the sleeve 43 is shaped to seat accurately against the shoulder 42 so as to prevent injury to the yarn by being pinched between the bottom of the sleeve and the shoulder 42 due to any irregularities in the mating surfaces.

Although a specific embodiment of the invention has been shown for purposes of illustration it is to be understood that the invention is capable of various uses and that changes and adaptations may be made therein as will be apparent to a person skilled in the art.

What is claimed is:

1. Apparatus for crimping yarn comprising a member having a bore extending therethrough, a tube extending through said bore and secured to said member, a pair of feed rolls disposed to feed said yarn into one end of said tube, said tube having a saddle disposed at the bite of said feed rolls to form a confined crimping chamber in which said yarn is crimped as it is fed by said rolls against a mass of yarn held compacted in said tube, said tube having an enlarged bore beginning at a point adjacent to the crimping chamber and extending to the other end of said tube, a sleeve disposed in said enlarged bore and forming a continuation of said crimping chamber, said enlarged bore forming an annular passage around the outside of said sleeve communicating with said crimping chamber, means including a port in said tube to supply a treating fluid to said annular passage, and take-up means to withdraw the crimped yarn under tension from said sleeve after passing as a compacted mass through said crimping chamber and through said sleeve.

2. Apparatus for crimping yarn comprising a member having a bore extending therethrough, a tube extending through said bore and secured to said member, a pair of feed rolls disposed to feed said yarn into one end of said tube, said tube having a saddle disposed at the bite of said feed rolls to form a confined crimping chamber in which said yarn is crimped as it is fed by said rolls against a mass of yarn held compacted in said tube, a sleeve disposed within said tube and adjustably secured thereto, said sleeve extending from the other end of said tube toward said first mentioned end and having an inner passage

forming a continuation of said crimping chamber, means supplying a treating liquid to said sleeve including a port in the upper part of said sleeve above said tube, a source of liquid supply and connections feeding liquid from said source through said port into said sleeve, and take-up means to withdraw the crimped yarn under tension from said sleeve after passing as a compacted mass through said crimping chamber and through said sleeve.

3. Apparatus for crimping yarn comprising a member having a bore extending therethrough, a tube extending through said bore and secured to said member, a pair of feed rolls disposed to feed said yarn into one end of said tube, said tube having a saddle disposed at the bite of said feed rolls to form a confined crimping chamber in which said yarn is crimped as it is fed by said rolls against a mass of yarn held compacted in said tube, a sleeve disposed within said tube and adjustably secured thereto, said sleeve extending from the other end of said tube toward said first mentioned end and having an inner passage forming a continuation of said crimping chamber, and means supplying treating liquid to said sleeve including a cup carried by said sleeve above said tube, means maintaining said liquid at a predetermined level in said cup, said sleeve having a port below said liquid level and valve means controlling the flow of liquid through said port into said sleeve and take-up means to withdraw the crimped yarn under tension from said sleeve after passing as a compacted mass through said crimping chamber and through said sleeve.
4. Apparatus for crimping yarn comprising a member having a bore extending therethrough, a tube disposed in said bore, a pair of feed rolls disposed to feed said yarn into one end of said tube, said tube having a saddle disposed at the bite of said feed rolls to form a confined crimping chamber in which said yarn is crimped as it is fed by said rolls against a mass of yarn held compacted in said tube, said tube having an enlarged inner bore beginning at a point adjacent to the crimping chamber and extending to the other end of said tube, a sleeve disposed in said enlarged bore and having an inner passage forming a continuation of said crimping chamber, and means securing said sleeve for axial adjustment with respect to said tube.
